United States Patent Office

Des. 191,835

Patented Nov. 28, 1961

191,835

DUTCH OVEN

John W. Ebstein, Roslyn Heights, N.Y., assignor to Federal Enameling & Stamping Company, Pittsburgh, Pa., a corporation of Michigan

Filed Sept. 12, 1960, Ser. No. 62,108

Term of patent 14 years

(Cl. D44—1)

FIG. 1

The dominant features of my design are shown in full lines.

I claim:

The ornamental design for a dutch oven, as shown and described.
